UNITED STATES PATENT OFFICE.

EMIL F. SCHULTZ, OF CLEVELAND, OHIO.

FASTENER.

SPECIFICATION forming part of Letters Patent No. 451,845, dated May 5, 1891.

Application filed August 8, 1890. Serial No. 361,482. (No model.)

To all whom it may concern:

Be it known that I, EMIL F. SCHULTZ, of Cleveland, in the county of Cuyahoga and State of Ohio, have invented certain new and useful Improvements in Fasteners; and I do hereby declare the following to be a full, clear, and exact description of the invention, such as will enable others skilled in the art to which it pertains to make and use the same.

10 My invention relates to improvements in fasteners that are designed more especially for attaching papers to either side or both sides of the article to which it is secured; and it consists in certain features of construction, and in combination of parts hereinafter described, and pointed out in the claim.

In the accompanying drawings, Figure 1 shows a fastener-blank as it comes from the dies. Figs. 2 and 3 are respectively a side 20 and edge view of the finished fastener; and Figs. 4 and 5 show said fastener secured to a piece of card-board, Fig. 5 showing a paper attachment to one side of the card-board. Figs. 6, 7, 8, and 9 illustrate a slight modification.

The fastener-blank is cut from suitable sheet metal, preferably sheet-brass.

A represents a blank as it comes from the dies, suitable for making my improved fastener. The blank has long narrow longitudinal slits *a'*, *b'*, and *c'*, that are parallel with one another, or approximately so, the central portion of the blank, from side to side, being imperforate. Slits *a'* *b'* *c'* divide the blank 30 into four divisions or leaves, *a*, *b*, *c*, and *d*. Now by folding or collapsing the outer leaves *a* and *d* against the intermediate leaves *b* and *c* and then folding or collapsing the latter, or vice versa, the fastener shown in Figs. 2 and 40 3 is formed.

In applying the fastener to the article to which it is to be secured—for instance, as shown in Figs. 4 and 5, to a piece of card-board—the fastener is passed through the 45 card-board until the imperforate portion *i* of the fastener has fully entered the card-board. The protruding portions of two of the leaves (in the instance shown the outer leaves *a* and *d*) are then folded down or clinched onto 50 the card-board, and this constitutes the head of the fastener, securely holding the latter in place. The remaining two leaves (*b* and *c*)

constitute the shank of the fastener, and the protruding portions of these leaves constitute the blades of the shank. 55

In Fig. 4 the blades of the shank are shown in position to receive papers on either side of the card-board, and Fig. 5 shows a paper attached to the card-board on one side thereof, the blades of the shank being clinched or 60 folded down onto the attached paper for holding the latter in place.

A slight modification is illustrated in Figs. 6, 7, 8, and 9. In Fig. 6, that shows the blank, leaves *c* and *d* are left imperforate, having no 65 slits between them. The folding or collapsing operation in making a fastener from this blank is, however, the same as that already described, the blank being shown partly folded in Fig. 7, and the finished fastener being shown 70 in Figs. 8 and 9, the latter showing it in position secured to a piece of card-board, leaves *c* and *d* forming the head in this instance, and leaves *a* and *b* the shank, the head thus being double and entirely to one side of the shank. 75 The paper-fasteners heretofore in use were objectionable because they had no provision for positively holding them in place on the backing, and consequently the fasteners would "slip out" in attaching and removing 80 papers.

With my improved construction, the head of the fastener being clinched or folded down on both sides of the article to which the fastener is secured, the fastener and attached 85 papers cannot possibly become displaced, and papers, &c., can readily be detached from either side of the backing without disturbing those on the opposite side.

In stationery, dry-goods, and other stores 90 samples of cloth, paper, &c., are frequently attached to both sides of a backing for showing to customers, and often it is desired to detach one or more samples from either side of the card-board; also, in banking-houses 95 papers are often fastened to both sides of a leaf in a journal or other books, and it is not unfrequently desired to detach one or more of such papers from either or both sides of the leaf. In either of these cases and many 100 others it is of considerable importance and a great convenience to be able to detach papers or samples as aforesaid from either side of the article to which they are attached with-

out displacing or disturbing the papers on the other side and without liability of the fastener "slipping out," and hence my improved fastener will be found invaluable in either of the 5 foregoing and in many other instances.

The construction of my improved fastener is simple. There is comparatively no waste of material, and hence the cost is reduced to a minimum.

10 What I claim is—

As an article of manufacture, a fastener composed of a single piece of material cut to form oppositely-extending leaves and having an imperforate central portion between the 15 leaves, the leaves adapted to be folded together

and the imperforate central portion of the fastener adapted to lie in an opening formed in a suitable backing to which the fastener is attached, one or more leaves adapted to be bent to clamp the fastener in place, and the rest of the leaves forming shanks on one or both sides of the article to secure papers or similar devices, substantially as set forth.

In testimony whereof I sign this specification, in the presence of two witnesses, this 25 14th day of July, 1890.

EMIL F. SCHULTZ.
